UNITED STATES PATENT OFFICE.

WILLIAM H. BRISTOL, OF WATERBURY, CONNECTICUT, ASSIGNOR TO THE BRISTOL COMPANY, OF WATERBURY, CONNECTICUT, A CORPORATION OF CONNECTICUT.

HYGROMETER.

1,176,425.

Specification of Letters Patent. Patented Mar. 21, 1916.

Application filed September 8, 1914. Serial No. 860,771.

To all whom it may concern:

Be it known that I, WILLIAM H. BRISTOL, a citizen of the United States, and a resident of Waterbury, in the county of New Haven 5 and State of Connecticut, have invented certain new and useful Improvements in Hygrometers, of which the following is a specification.

The invention relates to hygrometers, 10 more particularly to hygrometers of the wet and dry bulb thermometer type wherein the humidity is measured by the cooling effect of the evaporative power of the atmosphere at different temperatures and different percentages 15 of saturation. In hygrometers of this type, the wet bulb member is generally covered with absorbent material adapted to be suitably moistened; but, owing to the fact that the fibers of the material become coated 20 with dust and dirt and the pores of the material filled therewith so that said material is no longer hygroscopic, frequent change of the covering is necessary, for the instrument, otherwise, would indicate in an erratic and 25 grossly inaccurate manner.

It is the object of the present invention to avoid the necessity of such change or renewal of the covering and to provide a hygrometer which may operate for considerable 30 periods of time without impairment of the accuracy of its indications.

A further object of the invention is to prevent matter which may have gone into solution from depositing on said wet bulb during 35 evaporation.

The nature of the invention will be best understood when described in connection with the accompanying drawings, in which—

Figure 1 is a diagrammatic view illustrating 40 the improved hygrometer installed in a dry kiln or the like. Fig. 2 is a plan of the wet and dry bulbs of the hygrometer and support therefor. Fig. 3 is an end view of the same. Fig. 4 is a cross-section taken on 45 the line 4—4, Fig. 2.

Similar characters of reference designate corresponding parts throughout the several views.

Referring to the drawing, 7 and 8 designate 50 respectively the wet and dry bulbs of thermometers of any suitable type, the bulbs in the present instance being gas filled and connected with a measuring instrument 9 through suitably protected capillary tubes 55 10. The instrument is located at the desired

distance from the point where the humidity is to be measured, for example in a dry kiln or the like 11 and into which the bulbs 7 and 8 are inserted, as shown. These bulbs are mounted in a suitable supporting frame 60 work 12 and to the upper end of which is secured a casing 13 affording a water supply chamber which is in communication through a supply pipe 14 with a suitable tank 15 containing the water. From this tank, the water is automatically fed to the said chamber as required, the level of water in the latter being maintained constant as is well understood. A strip or cloth or textile fabric 65 16, providing a suitable covering or wick for the wet bulb, extends from casing 13 and is arranged to substantially cover the surface of said bulb and from which it extends downwardly below the level of the water in casing 13 and, preferably, also below said 70 bulb. The lower end is placed in a casing 17 attached to the underside of the frame 12 and forming a chamber or receptacle for the surplus water from said wet bulb covering. An overflow pipe 18 communicates with the 75 interior of said casing 17 to remove the surplus water therefrom and extends beyond the kiln 11, its outlet being at the proper height to maintain the desired level of the water in the casing 17. A siphon action is 80 thereby afforded and by means of which the water is continuously and progressively supplied to said cover or wick 16 from the casing 13 and delivered into the casing 17, from whence the surplus is removed as here- 85 before described. This will effect the removal of any dirt or dust from the covering, and which would otherwise settle thereon and impair the reliability of the instrument, and will carry along, also, any matter which 90 might go into solution and tend to deposit on the bulb during evaporation. The cover will, therefore, render satisfactory service for long periods of time without necessitating renewal or the use of mechanical devices for 95 advancing or cleaning the same. 100

I claim:—

1. In a hygrometer: a wick member; a casing providing a water supply chamber into which said wick member dips; and a 105 wet bulb member outside the water of said water supply chamber and in contact with said wick, which latter has a portion extending outside said casing and its end below the level of the water therein 110

and extending beyond the said wet bulb member.

2. In a hygrometer: a wick member; a casing providing a water supply chamber into which one end of said wick member dips; and a wet bulb member located outside of said casing below the level of water therein and in contact with the outer portion of said wick, the end of which extends below the level of the water and beyond the said wet bulb member.

3. In a hygrometer: a wick member; a casing providing a water supply chamber into which one end of said wick member dips; and a wet bulb member outside the water of said water supply chamber and in contact with said wick, the other end of which extends outside said casing and below the level of the water therein.

4. In a hygrometer: a wick member; a casing providing a water supply chamber into which one end of said wick member dips; a second casing located below the level of the water in said water supply chamber and into which the other end of said wick dips; and a wet bulb member outside the water of said water supply chamber and in contact with the outer portion of said wick.

5. In a hygrometer: a wick member; a

casing providing a water supply chamber into which one end of said wick member dips; a second casing located below the level of the water in said water supply chamber and into which the other end of said wick dips; a wet bulb member outside the water of said water supply chamber and in contact with the outer portion of said wick; and an overflow pipe from said second casing.

6. In a hygrometer: a wick member; a casing providing a water supply chamber into which said wick member dips; a wet bulb member outside the water of said water supply chamber and in contact with said wick, which latter has a portion extending outside said casing with its end below the level of the water therein and extending beyond the said wet bulb member; and a water containing vessel in communication with said water supply chamber to afford a continuous supply of water thereto.

Signed at New York, in the county of New York, and State of New York, this 3rd day of Sept. A. D. 1914.

WILLIAM H. BRISTOL.
